UNITED STATES PATENT OFFICE

2,440,990

TABLE AND IRONING BOARD

Mary E. Van Dusen, Yale, Mich.

Application July 30, 1945, Serial No. 607,682

2 Claims. (CL 38—105)

1

This invention relates to a combined table and ironing board and it is one object of the invention to provide a table which may be used as a general utility table in a kitchen or laundry and has an ironing board so associated with it that it may be normally disposed under the top of the table but readily moved into position over the table top for use.

Another object of the invention is to provide a table, having its top formed of sections, one of which is hinged for movement from a position flush with its other section to a position in which it rests upon the second section and disposes an ironing board carried by the hinged section in position for use.

Another object of the invention is to provide a table, wherein the hinged section of the top is so disposed that when the ironing board carried thereby is under the table it will not interfere with opening and closing of drawers of the table.

Another object of the invention is to so connect the ironing board with the hinged section of the table top that it may be moved from a position close against the table top to an elevated position and releasably secured in the raised position.

Another object of the invention is to provide a combined table and ironing board which will be of attractive appearance and very strong.

The invention is illustrated in the accompanying drawings, wherein:

Figure 1 is a perspective view showing the ironing board in position for use.

Figure 2 is a sectional view taken along line 2—2 of Figure 1.

Figure 3 is a view showing the table and ironing board principally in elevation and partially in longitudinal section.

Figure 4 is a sectional view taken transversely through the table with the ironing board in position under the table top.

Figure 5 is a sectional view taken longitudinally through the table along line 5—5 of Figure 4.

Figure 6 is a view in front elevation, showing the ironing board in position for use and secured in its raised position.

Figure 7 is a view similar to Figure 6 showing the ironing board in partially lowered position.

Figure 8 is a fragmentary view showing the ironing board fully lowered.

The table has a top including a fixed section 1 and a movable section 2 which is connected with the fixed section by hinges 3 so that it may be swung from the lowered position of Figure 4 to the raised position of Figure 2 in which it rests

flat upon the upper surface of section 1. The section 1 is firmly secured to side rails forming a frame 4 and at corners of the frame are legs 5 which are held in place by brackets 6 and have their upper ends flush with upper edge faces of the side rails forming the frame. A long drawer 7 is slidably mounted upon tracks for opening and closing movement through an opening 8 at the front of the frame and at opposite sides of the table are chambers, each normally closed by a door 10. An iron and other articles used when pressing clothes may be stored in the chambers and in the drawer 7. There has also been provided a support 11 upon which an iron may be set, the iron stand or support 11 being formed of metal, woven wire, or other suitable material. Blocks or strips 12 are secured against inner side faces of end portions of the frame and are spaced downwardly from upper edges thereof so that when the section 2 is in its lowered or closed position the ironing board 13, carried by this section, may rest upon the blocks.

The ironing board is formed of wood or other suitable material and in order to connect the board with section 2 there have been provided strips 14 of angle metal and links 15 formed from metal strips of suitable length. The strips 14 are secured against the section 2 of the table top longitudinally thereof with flanges projecting therefrom, and the links 15 have their ends pivoted to the flanges of the strips 14 and to side edge faces of the ironing board. Since the links 15 are pivoted to the ironing board and to the strips 14, the ironing board may be shifted vertically from a position close to the top section 2, as shown in Figure 8, to a partially or fully raised position, as shown in Figures 7 and 6, and thus allow the board to be adjusted for convenient use by a tall or short person. Latching strips 16 are pivoted to the strips 14 at ends of the links near one end of the mounting strips and each is formed near its free end with notches 17 and 18 for receiving pins 19, so that the ironing board may be firmly held in a partially raised position or a fully raised position and prevented from moving downwardly to the lowered position of Figure 8 when subjected to the weight and pressure of an iron. Since edge portions of the top sections protrude from edges of the frame 4 the top section may be easily grasped when in the lowered or closed position and swung upwardly to the position of Figures 1 and 2, where it rests flat upon the top section 1 in position for use of the ironing board. When the top section is swung to its closed position, it rests upon the frame and ends of the iron-

ing board rest upon the blocks 12. Therefore the board will be supported under top section 2 and the links will not be subjected to strains which might cause the fasteners connecting them with the board and the strips 14 to be broken. Sheets or other large articles may rest flat upon the ironing board and be shifted downwardly back of the two top sections into a basket placed under the table, and certain articles may be slipped about the free end portion of the ironing board when the ironing board is supported in the raised position of Figure 6 or Figure 7.

Having thus described the invention, what is claimed is:

1. A combined table and ironing board, comprising a table, having a frame and top sections, one top section being fixed to the frame and the other top section being mounted for swinging movement from a position flat upon the frame back of the fixed section to a raised position flat upon the fixed section, an ironing board, strips of angle metal mounted along the movable top section, links formed of flat strips of stiff metal spaced from each other longitudinally of the strips of angle metal and having their ends pivoted to the angle metal strips and to side edge faces of the ironing board, a latching strip formed from a flat strip of stiff metal and having one end pivoted at the lower end of a link adjacent one end of one of said angle metal strips, a pin projecting outwardly from another link pivoted to the angle metal strip, said latching strip being of a length adapting it to extend across the last mentioned link and having its free end portion formed with longitudinally spaced notches for selectively receiving said pin and releasably holding the ironing board spaced upwardly from the movable top section a predetermined distance, and blocks mounted against inner surfaces of end portions of said frame constituting supports for ends of the ironing board when the movable section is resting upon the frame in back of the fixed section.

2. A combined table and ironing board, comprising a table, having a top including a fixed front section and a rear section hinged to the front section for swinging movement from a closed position back of the front section to an opened position in which it rests upon the front section, strips of stiff angle metal extending longitudinally of the movable rear section and having side flanges projecting upwardly from a movable section when the movable section is in its opened position, an ironing board, links formed from flat strips of stiff metal spaced from each other longitudinally of the angle metal strips and pivoted at their ends to inner side face of the flanges of the said angle metal strips and to opposite side edge faces of the ironing board and mounting the board for vertical shifting from a position close against the movable top section to a position in spaced relation thereto, and a latch consisting of a flat strip of stiff metal extending longitudinally of one of said angle metal strips and mounted for movement into and out of engagement with one of the links for securing the ironing board in spaced relation to the movable top section.
